Maurin *Plumb*

UNITED STATES PATENT OFFICE

JOSEPH W. BERESFORD, OF CLIFTON, NEW JERSEY

FOUNTAIN TOOTHBRUSH

Application filed April 1, 1931. Serial No. 526,793.

This invention relates to improvements in brushes, particularly tooth brushes, and it is the principal object of my invention to provide a tooth brush having means for ejecting a paste contained in the hollow handle of the brush to the bristles in any desired quantity.

Another object of my invention is the provision of a fountain tooth brush the handle of which is composed of two parts, one of which contains the paste and the other provided with a bore having a conical cavity at its end to receive the paste, and communicating at its opposite end with a bore in a brush head to supply the bristles with the quantity of paste from said handle.

These and other objects and advantages of my invention will appear as the description thereof proceeds and will then be specifically defined in the appended claims.

In the accompanying drawing forming a material part of this disclosure:

Fig. 1 is a longitudinal sectional view of a tooth brush constructed according to my invention.

Fig. 2 is a top plan view thereof.

Fig. 3 is a cross-sectional view on line 3—3 of Figure 1.

Fig. 4 is a cross-sectional view on line 4—4 of Figure 1.

Fig. 5 is a fragmentary longitudinal sectional view of the brush head.

As shown in Figures 1 to 5, the handle of a tooth brush is composed of two sections 10 and 11 preferably hexagonal in cross-section in order to provide an effective grip. The outer section 10 hollow and provided with inner thread 12 adapted to receive the enlarged end of the inner section 11 provided

40 with an external thread at its end.

The outer section is adapted to be filled with a paste 13, and carries at its outer end a knob 14. The inner section has a longitudinal central bore 15 having a conical entrance

45 16 at the end in communication with the paste containing outer section and at its opposite end with a central longitudinal duct 17 of a brush head 18, the shank 19 of which is threaded into the end of the inner section

50 as at 20. The duct 17 in this shank has a

right angled outlet 21 between the bristles 22 held in the head in the usual well known manner and extending through a cover plate 23.

It will be clear that I may make such changes in my construction as come within the scope of the appended claims, without departure from the spirit of my invention.

Having thus described my invention what I claim as new and desire to secure by Letters Patent is:—

1. A tooth brush comprising an elongated head of semi-elliptical cross section having a cylindrical shank provided with an external thread and containing a duct, a bristle carrying plate secured on the flat side of said head having a central opening communicating with the duct, a tubular paste container handle having a cap at its outer end and provided with an internal thread, and a connector element of hexagonal cross section provided with a bore, an internal thread to engage the shank of said head, an enlarged externally threaded opposite end to engage said handle and a conical cavity within the enlarged end open to its bore.

2. A tooth brush comprising an elongated head of semi-elliptical cross section having a cylindrical shank provided with an external thread and containing a duct, a bristle carrying plate secured on the flat side of said head having a central opening communicating with the duct, a tubular paste container handle having a threaded cap at its outer end and provided with an internal thread for receiving the threads of the cap to facilitate the filling of cream or paste to the handle, and a connector element of hexagonal cross section provided with a bore, an internal thread to engage the shank of said head, an enlarged externally threaded opposite end to engage said handle and a conical cavity within the enlarged end open to its bore.

In witness whereof I have signed my name to this specification.

JOSEPH W. BERESFORD.
